UNITED STATES PATENT OFFICE.

JAMES L. HOSACK, OF ANN ARBOR, MICHIGAN, ASSIGNOR TO WENDELL P. MOORE, OF ANN ARBOR, MICHIGAN.

BLOCK-DROPPER FOR HAY-PRESSES.

No. 800,109.

Specification of Letters Patent.

Patented Sept. 19, 1905.

Application filed August 8, 1903. Serial No. 168,771.

To all whom it may concern:

Be it known that I, JAMES L. HOSACK, a citizen of Great Britain, residing at Ann Arbor, county of Washtenaw, State of Michigan, have 5 invented a certain new and useful Improvement in Block-Droppers for Hay-Presses; and I declare the following to be a full, clear, and exact description of the invention, such as will enable others skilled in the art to which it pertains to make and use the same, reference being had to the accompanying drawings, which form a part of this specification.

My invention relates to hay-presses, and more particularly that part thereof which is 15 termed a "block-dropper," and has for its object a construction which shall permit the dropper to be held in such manner that it is pivoted out of the way until it is needed for use and then is swung around over the feed- 20 opening at the proper time to place the division-block; and it consists in the combinations hereinafter described and claimed.

In the drawings, Figure 1 is a side elevation of a hay-press of the general type heretofore 25 described and patented in Patent No. 700,698, dated May 20, 1902, issued to Eli W. Moore, and about which no general description is necessary. Fig. 2 is a partial plan view of the same, showing the division-block in position. 30 Fig. 3 is a perspective view showing the mechanism for holding and swinging the division-block. Figs. 4, 5, 6, and 7 are perspective views, upon an enlarged scale, of the details of mechanism shown in Fig. 3.

Similar letters refer to similar parts.

In the drawings, A represents the upper portion of the frame of the machine; B, the beater; C, the bottom portion of the frame.

In Fig. 1 a portion of the frame and side is 40 shown broken away to show the internal construction, and the dotted lines show the division-block D in position when forced down. Upon the beater-frame is fastened a triangular iron E, which at the proper time engages the 45 block D (shown in section in Fig. 1) and forces it into the position shown in the dotted lines in the manner hereinafter described.

The holder for the division-block D consists of a gate which is made up of several parts. 50 These are two side pieces, one of which is shown in Fig. 6 as G, each having L-shaped brackets at each end, (marked g' g'.) These brackets are perforated at g' for a purpose hereinafter stated. Projecting from the

brackets longitudinally are two lugs H H. 55 Two of these standards G G are united by a sheet-metal plate J, being attached thereto, and to one of them is bolted a handle K. The opposite end engages, by means of the holes g' g', a spindle L, upon which the whole 60 structure turns. Upon the upper ends of the brackets G G are attached cheek-pieces M, one of which is shown in Fig. 5 in detail. These carry strong springs S S, the office of which is to compress the division-block D between the spring and the uniting-plate J, it being held from endwise movements by the pieces G G, and this holds it in line with the interior or side walls of the press. The spindle L is supported in the following manner: Upon each side of A there is bolted a metal bracket or casting N'. (Shown in elevation in Fig. 7 and also in perspective in Fig. 3.) Supported upon this bracket on one side of the machine is a reversible support-block N, adapted to be placed on either side by reversing the ends and having a vertical hole P, through which the spindle L extends. Thus the spindle L engages in the hole P in the casting N'. The upper surface of this casting is peculiarly shaped, in that it has two depressions P' P', both of which are exactly alike, except that they are reversed. At one end of each depression P' there is a slightly-deeper depression P'', which does not 85 possess sharp angles, but is intended to receive the projection H as the part G swings upon the pivot L. When the gate is in the position of Fig. 3, the projection H comes up close to a projection N' of the block N. When 90 the gate is swung longitudinally with the frame A, the projection H engages in the depression P'' and holds the gate in this position until some force is applied to the handle K, by which it is lifted from the detent P'' and 95 may be swung crosswise of the machine and in position where the angle-iron E is enabled to strike it and force it downward. The angle-iron E is shown as partially forcing the division-block D down about half-way in 100 Fig. 3.

With reference to the block N the object of making two depressed parts P'' P'' alike, except reversed, and also of making the two side pieces G G exactly alike is so that by 105 detaching the block N from the frame A it can be attached to the opposite side and by disassembling the parts they can be reassembled

in reverse position, so that the left-hand block G in Fig. 3 becomes the supporting one, and the gate then swings with the hands of a watch, whereas in the position shown in Fig. 5 3 the gate swings to swing shut or crosswise of the machine against the hands of a watch. By this means a very convenient and efficient support is formed to support the division-block until it is forced down at the proper instant 10 to divide the preceding bale from the one under process of construction in the hay-press.

The operation of the device is obvious from the foregoing description.

What I claim is—

- 15 1. In a division - block support for a hay-press, the combination of the main frame, a reversible block attached thereto supporting a pivotal standard, a gate supported upon said standard and held frictionally upon said supporting-block, means upon said gate for supporting a division-block and means for swinging said gate into a position to be operated upon, and means for driving said block home, substantially as described.
- 20 2. The combination of a casing, a bearing adapted to be fixed to each side thereof, a reversible gate adapted to be supported by the bearing in each position, a pivot supported by said bearing, said gate being supported upon said reversible block, and means for driving the division - block, substantially as described.
- 25 3. In means for supporting divisional-block supports for hay-presses pivotally upon the hay-press, the combination of a bracket located at each transverse side of said block, said brackets being united by a plate, and elastic means carried by said brackets for frictionally engaging the ends of said block 40 and supporting same therein and said division-block, substantially as described.
- 30 4. In a hay-press, the combination with a frame having two sides, of a spindle L, and a block-holder revolubly attached to said spindle, said block - holder carrying a division-

block whereby the holder may be reversed with reference to the frame, substantially as described.

5. In a baling-press, in combination, a chest having a top feed-aperture, and a block-carrier pivoted vertically at the sides of the chest and oscillating over the top thereof. 50

6. In a baling-press, in combination, a chest having a top feed - aperture, a block - carrier pivoted vertically at the side of the chest and oscillating over the top thereof, and a feeder oscillating into and out of the feed-aperture and having a block-engaging lug. 55

7. In a baling-press, in combination, a chest having a top feed-opening, a reversible block-carrier, and means for pivoting the carrier vertically at either side of the chest, so that it may oscillate over the top thereof. 60

8. In a baling-press, in combination, a chest having a top feed-opening, a carrier having 65 vertical block - receiving ways open at both ends, a shaft to which the carrier is hinged, and a bracket attached to each side of the chest and having a vertical socket for receiving the shaft. 70

9. In a baling-press, in combination, a chest having a top feed-aperture, a block - carrier pivoted vertically at the side of the chest and oscillating over the top thereof, and a stop for limiting the forward movement of the 75 carrier.

10. In a baling-press, in combination, a chest having a top feed-opening, a bracket secured to the side of the chest and having a stop-lug, a shaft rising from the bracket, a block-carrier hinged to the shaft so as to oscillate over the chest, and lug on the hinge of the carrier for engaging the stop-lug of the bracket. 80

In testimony whereof I sign this specification in the presence of two witnesses.

JAMES L. HOSACK.
